UNITED STATES PATENT OFFICE.

MELZAR G. TURNER, OF WESTBOROUGH, MASSACHUSETTS, ASSIGNOR TO THE TURNER MANUFACTURING COMPANY, OF CONCORD, NEW HAMPSHIRE.

SEPARATOR-PLATE FOR SEWING-MACHINES.

SPECIFICATION forming part of Letters Patent No. 406,816, dated July 2, 1889.

Application filed November 26, 1887. Serial No. 256,227. (No model.)

To all whom it may concern:

Be it known that I, MELZAR G. TURNER, of Westborough, county of Worcester, and State of Massachusetts, have invented certain new and useful Improvements in Sewing-Machines, of which the following is a specification, reference being had to the drawings accompanying and forming a part hereof, in which—

Figure 1 is a front elevation of the machine above the work-plate so far as necessary to show my improvements. Fig. 2 is a top view, looking down from the line x x , Fig. 1. Fig. 3 is a front end view of a complete machine embodying my invention.

15 My present invention is an improvement on the invention shown and described in Letters Patent No. 312,306, dated February 17, 1885, granted to me. In the device there shown and described the separator-plate is secured directly to the work-plate, and so obstructs the passage of the work over the work-plate as to limit the use of the machine to ruffling, which is made on or near the edge of the piece of cloth or fabric. The separator-plate as constructed in the machine set forth in my said patent is incapable of being easily raised to admit of the insertion of the work, and this is also objectionable.

20 To avoid these objectionable features is the chief object of my present invention, which consists in a separator-plate constructed and mounted as hereinafter more fully described, in combination with a ruffler-feed below the work-plate.

35 As my invention may be applied to various forms of machines adapted to do ruffling which are well known, I need not describe such machines in detail, and will confine my description to my present improvements. One 40 form of such machine is set forth in my patent, No. 312,306, to which I have already referred.

The letters of reference will be found on the accompanying drawings, and are used to 45 designate the parts referred to.

A represents the work-plate, and B a part of the frame of the machine which supports the needle and presser-foot bars C and D, respectively. To the frame, directly behind the 50 needle and presser-foot bars, I secure an arm

E, which I prefer to make in the curved form shown. The arm E carries the separator-plate J, the lower end of the arm being above the work-plate A a sufficient distance to enable the work to be freely passed under the arm 55 and under the separator-plate at the point at which the plate is attached to the arm.

The separator-plate J is preferably of the form shown in Fig. 2, the end a of the rear portion thereof being turned upwardly, forming a flange at right angles to the body of the plate to enable the plate to be pivoted, as shown at b , to the lower end of the arm E, the pivot extending through the flange a and the lower end of the arm. A stud m , set in the 60 arm E, projects through a short slot in the flange a and assists in securing the separator-plate in position and steadyng it in its movements.

To the lower end of the arm, and in front thereof, I pivot a lever H for raising the separator-plate when the work is being inserted and throwing it down upon the work and holding it there when the work is in the machine. The lever H is provided with two projections c and d . The projection c is in front of the pivot, and serves to throw and hold the plate down, so that its forward end rests upon the work, as shown in full lines, Fig. 1. The projection d on the opposite side of the pivot 80 of lever H serves to raise the plate when the lever is thrown down, as shown by the dotted lines, Fig. 1.

The separator-plate has a certain amount of spring, and its inner end, which is over the 85 ruffler-feed, is thus held in spring contact with the upper surface of the work, while the under surface of the work is being acted on by the ruffler feed or blade L, carried by the block M beneath the work-plate A, said block 90 being operated by the eccentric N and spring O, as in my patent, No. 312,306, hereinbefore referred to.

In the operation of my device the fabric to be ruffled passes between the work-plate A 95 and the separator-plate J, the fabric to which the ruffle is to be sewed passing above the said separator-plate. The ruffler-feed L has a longer throw than the work-feed P. In operation the said ruffler-feed is moved upward 100

through an opening in the work-plate into contact with the fabric passing below the separator-plate and then forward to form the ruffle or gather, which is sewed to the super-
posed fabric by the stitch-forming devices, the ruffling operation being thus essentially the same as in the machine shown by my patent hereinbefore mentioned.

An edge-guide is shown at K, secured in
10 the usual manner on the work-plate. When, however, the machine is to be used on wide fabric, this edge-guide is removed.

In putting work into or taking it from the machine the lever H is thrown up, raising the
15 separator-plate, so as to permit the work to be freely passed under it. When the work is in position, the lever is raised and the forward or inner end of the separator-plate is thrown down, holding the work against the ruffler-
20 feed.

As will be obvious, the separator-plate may be rigidly secured to the arm E instead of being pivotally connected therewith, in which case the lever H will not be required. I prefer, however, to construct the separator-plate
25 as shown for convenience in getting the work into and out of the machine.

What I claim is—

1. In a sewing-machine, the combination, with a ruffler-feed below the work-plate and 30 means for operating said ruffler-feed, of the supporting-arm E, secured to the frame of the machine above said work-plate, the separator-plate J, pivotally attached to said arm, and a lever also pivoted to said arm and having a part or projection, as c, to engage the said separator-plate forward of its pivotal point, and thus depress the forward end of said plate, substantially as set forth.

2. In a sewing-machine, the combination, 40 with a ruffler-feed arranged below the work-plate and means for operating said ruffler-feed, of a supporting-arm E, secured to the machine-frame above the work-plate, a separator-plate J, pivoted at its rear end to the 45 said arm E, and the lever H, also pivoted to said arm and having projections c d on opposite sides of its pivotal point to engage said separator-plate and depress or raise the forward end thereof, substantially as set forth.

MELZAR G. TURNER.
